FURNACE STOKER

Bert Coleman and Silas J. Hendershott, Detroit,
Mich., assignor to Ever-Ready Coal Burner
Company, Detroit, Mich., a corporation of
Michigan

Application September 2, 1930. Serial No. 479,354

3 Claims. (Cl. 126—170)

The invention relates to automatic stokers for domestic heating furnaces and more particularly to a construction providing for the shaking of the furnace grates either automatically or manually.

5 The object of the invention is to provide an improved construction for the operation of the grates constructed in a simple manner and arranged for convenient access for the manual operation of the grate. A further object is to provide 10 an automatic mechanism for operating the grates during the automatic operation of the furnace so as to obtain an efficient operation of the furnace.

These and other objects are attained in the 15 construction hereinafter described and illustrated in the accompanying drawings, wherein

Figure 1 is a side elevation with parts shown in section of a furnace stoker embodying our invention;

20 Figure 2 is an end view of the stoker;

Figure 3 is a transverse sectional view on the line 3—3 of Figure 1;

Figure 4 is a top plan view of a portion of the mechanism;

25 Figure 5 is a perspective view of the stoker mechanism;

Figure 6 is an enlarged sectional view of a portion of the structure shown in Figure 1.

Figure 7 is a sectional detail view of a portion 30 of the retort and grate.

In the construction as illustrated in the drawings, 1 represents a body portion or base above which is mounted the fuel hopper 2. The body 1 is hollow and is provided at the bottom thereof 35 with a transversely extending screw conveyor 3 which projects outwardly from the body and is enclosed by a laterally projecting tube 4. For driving the conveyor 3 there is an electric motor 8 connected to the conveyor through a suitable gear reduction mechanism 9 in the gear casing 10. The tube 4 communicates with a retort 5 consisting of an inner fuel reservoir 5a and an outer air chamber 5b. A top casting 6 connecting the inner and outer walls of the retort is 40 perforated by two series of holes, one series 6a directing the air inwardly and the other series 6b directing the air outwardly. The casting 6 also has laterally projecting fingers forming a stationary annular grate 6c. Surrounding the retort 5 is an oscillating grate 7 arranged slightly below the stationary grate 6c and forming the larger portion of the total grate area. The oscillating grate is suitably supported on ball bearings 8a 45 which in turn are carried by the race 8b formed by the lip 8c on the outer wall of the retort 5.

The stoker as described above is adapted for intermittent feeding of coal or other fuel from the hopper 2 into the furnace and the intermittent motion of the screw conveyor 3 is provided by the starting and stopping of the electric motor 8. The control of the motor 8 is preferably effected by means of a thermostatic mechanism which may be of any suitable type such as are commercially manufactured at the present time. For the preferred construction of the control mechanism reference should be made to our co-pending application, Serial No. 479,297, filed on even date herewith.

The motor shaft 60 extends through the gear casing 10 and on the opposite side of said casing connects with a suitable blower 61. This blower has an air tube 62 extending therefrom which is preferably arranged adjacent to the fuel tube 4. At the delivery end of the air tube there is an upwardly extending elbow 63 for discharging the air through the grates. There is also arranged at the elbow a clean-out door 64 for facilitating the removal of foreign matter from the air tube.

The driven shaft 65 projects through both ends of the gear casing 10, one end extending into the hopper base and connecting with the screw conveyor 3. The other end of the shaft 65 is provided with a disk 66 to which is eccentrically attached a link 67 for oscillating an arm 68 on a rocker shaft 69. This shaft 69 projects through the hopper base to the opposite side of said base and is provided with a second arm 70. 71 is a link connecting the arm 70 with the shaker arm 72 which in turn is mounted on a shaft 73 extending parallel to the fuel feed tube 4. The shaft 73 projects through the ash pit 74 of the furnace and is rotatably mounted in a suitable bearing 75 in a lug 76 projecting from said elbow 5. 77 is an arm attached to the shaft 73 and extending upwardly beneath the oscillating grate 7. This arm is connected to a pin 79 on the underside of the grate by means of a link 78.

The shaker arm 72 has at its outer end an arcuate portion 80 provided with smooth side bearing surfaces 81 and a centrally arranged notch 82. Adjacent the shaker arm and pivotally secured to the shaft 73 is a socket member 83, having at its upper end a laterally projecting tooth 84 adapted to ride on the bearing surfaces 81 or enter the notch 82 when in alignment therewith. The socket member has a bifurcated lower end embracing the shaft 73 and pivotally attached thereto by means of a pin 85, thus permitting the

socket member to swing toward or away from the shaker arm 72. A spring 86 arranged within a bore 87 bears against the shaft 73 and normally holds the tooth 84 in the cooperating recess 82. 88 is a removable handle member insertable within a socket 89 in the socket member and having the handle grip 90 at the upper end for facilitating manual operation of the shaker mechanism.

10 In the operation of the stoker the main driving motor 8 drives the blower 61 and induces a forced draft through the air tube 62 and into the fuel on the grates. The motor also drives the screw conveyor 3 at a reduced speed because of 15 the gear reduction in the gear box 10. The conveyor takes the solid fuel from the hopper and feeds it through the fuel tube 4 into the center of the retort 5.

The driven shaft 65 through the link 67 oscillates the shaft 69 and consequently oscillates the shaker arm 72 about the shaft 73. The degree of oscillation of the shaker may be regulated to a certain extent by inserting the connecting link 71 in one of the apertures 91 and 92 respectively, thereby obtaining a correspondingly greater or lesser amplitude of movement of the shaker arm.

In the usual position of the socket member 83 it is held in driving relation with the shaker member by the spring 86 which maintains the tooth 84 within the recess 82. In this position the shaft 73 is caused to oscillate with the shaker member 72 and this in turn oscillates the arm 77 and the oscillating grate 7. The arrangement 35 is such that whenever the stoker motor 8 is in operation the grate 7 is given a slow oscillatory movement, thereby freeing the grate from the ash and permitting ready access of the air through the grate.

40 When it is desired to manually operate the grates the handle member 88 is moved laterally about the pivot pin 85, disengaging the tooth 84 from the shaker arm and permitting the shaft 73 and the linkage to the grate 7 to be operated 45 independently of the stoker motor 8. After the manual operation is complete and the handle member is released the tooth 84 is moved into contact with the shaker member 72 by the spring 50 86 so that in the subsequent automatic oscillation of the shaker member the tooth 84 will always re-enter the recess 82 and couple the grate to the automatic shaking mechanism.

As heretofore stated, the stoker motor 8 is controlled by suitable thermostatic mechanism, the arrangement being such that the motor is intermittently operated and the duration of its operation depends upon the temperature conditions in the room heated by the furnace. It will be seen therefore that the intermittent operation 55 of the motor 8 not only intermittently feeds the coal to the fire pot but also intermittently feeds the air to the grate from the blower and intermittently agitates the grate for the removal of the ash. The mechanism as described functions as a 60 natural draft burner, the air for combustion being drawn through the grates into the fire pot in the same manner as a conventional furnace not provided with any stoker mechanism. It has been found, however, that the addition of

the small blower 61 aids in assuring complete combustion and it is therefore preferable to incorporate the same in the stoker mechanism as above set forth. It is to be understood, however, that the stoker mechanism in the preferred form 80 as outlined above is not a forced draft machine in the same degree as are other stoker mechanisms heretofore constructed.

What we claim as our invention:

1. In a domestic stoker, an oscillating grate, an oscillating shaft, a rocker member secured to said shaft, a link operatively connecting said grate and rocker member, an arm journaled on said shaft, means for automatically oscillating said arm in a plane transverse to said shaft, a member adapted to receive a handle and pivoted to said shaft for rocking movement toward and away from the plane of said arm, a tooth on said member extending toward said arm and drivingly engageable therewith when said arm is rocked toward said plane and releasable when said arm is rocked away from said plane, a spring normally urging said member toward the plane of said arm and a handle engaging said member for rocking the same away from said plane to release said tooth from said arm whereby said shaft may be oscillated independently of said arm.

2. In a domestic stoker, an oscillating grate, an oscillating shaft, a rocker member secured to said shaft, a link operatively connecting said grate and rocker member, an arm journaled on said shaft, said arm having a laterally extending flange forming a bearing face and provided with a notch therein, means for automatically oscillating said arm in a plane transverse to said shaft, a member adapted to receive a handle and pivoted to said shaft for rocking movement toward and away from the plane of said arm, a tooth on said member engageable with said notch in said arm when said member is rocked toward said plane and releasable when said member is rocked away from said plane, a spring normally urging said member toward the plane of said arm and a handle engaging with said member for rocking the same away from said plane to release said tooth from said notch whereby said shaft may be oscillated independently of said arm.

3. In a domestic stoker, an oscillating grate, an oscillating shaft, a rocker member secured to said shaft, a link operatively connecting said grate and rocker member, an arm journaled on said shaft, a fuel hopper, a rod extending through said fuel hopper, a driving motor, a connection for oscillating said rod from said driving motor, a connection for oscillating said arm from said rod, a member adapted to receive a handle and pivoted to said shaft for rocking movement toward and away from the plane of said arm, a tooth on said member engageable with said arm when said member is rocked toward said plane and releasable when said member is rocked away from said plane, a spring normally urging said member toward the plane of said arm and a handle engaging said member for rocking the same away from said plane to release said tooth from said arm whereby said shaft may be oscillated independently of said arm.

BERT COLEMAN.
